UNITED STATES PATENT OFFICE

HENRY W. HONEYMAN, JR., OF PROVIDENCE, RHODE ISLAND

WARP LOOPING MACHINE

Application filed April 22, 1930. Serial No. 446,230.

This invention relates to means for automatically hanging loops or folds of traveling warp over a support; and the object of this invention is to provide a machine to which 5 a continuous sliver or warp is fed, the machine being provided with a reciprocating warp conducting member arranged to swing back and forth to deposit or hang the warp in folds or loops on a bar or supporting member 10 to be subsequently transferred on this supporting member for further treatment.

A further object of the invention is the provision of traversing means for advancing the warp guiding member laterally, causing 15 the warp folds to lie side by side along its receiving bar.

A still further object of the invention is to provide a set of elongated feed rolls and providing a warp-receiving bar of a length 20 substantially that of the rolls over which the warp is laid or hung in folds or loops, the warp guide member being advanced along said feed rolls to lay the warp strands side by side along the length of the bar.

With these and other objects in view, the invention consists of certain novel features of construction, as will be more fully described, and particularly pointed out in the 25 appended claims.

In the accompanying drawings:

Fig. 1 is a front elevation of the machine.

Fig. 2 is an end elevation showing a portion of the frame removed.

Fig. 3 is a diagrammatic view showing the 30 means for driving the different elements of the machine.

Fig. 4 is a diagrammatic view showing a portion of the machine in perspective, and 35 illustrating the general arrangement of parts and the operation of the machine.

Fig. 5 is an enlarged sectional view of the 40 traversing screw shaft with its engaging lead pawl mounted in its nut.

Fig. 6 is a fragmental view of this screw 45 showing the shape of the groove at its end and the pawl mounted therein in the act of reversing its direction of travel.

Ordinarily in drying and otherwise treating 50 textile warps it is first hung by hand in folds over a bar and then the loaded bar is

removed to present the warp for further treatment and another bar positioned to receive the next load, but my improved machine serves to automatically hang or lay the warp over the continuously running bar 55 automatically during the operation of the machine; and to accomplish this automatic operation in a simple and effective way, I have provided a machine to which the continuous sliver or warp is fed, the machine being here- 60 in illustrated as having a pair of reciprocating rolls arranged to swing back and forth over the warp receiving bar to lay or hang the warp in folds or loops thereon, the bar being supported for ready removal together 65 with the warp hung thereon for further treating the warp; and the following is a detailed description of the present embodiment of my invention and showing the preferred construction of machine by which 70 these advantageous results may be accomplished:—

With reference to the drawings, 10 designates the framework of the machine on which is rotatably mounted an elongated upper 75 feed roll 11 and a similar cooperating lower feed roll 12 to which the warp 13 is fed over the guide roll 14 and thru the traversing guide eye 15, the warp being led from these feed rolls down thru the oscillating fold-laying rolls 16 and 17 which swing to hang 80 the warp upon the bar 18 supported below.

These rolls 16 and 17 are supported in bearings in the swinging arms 19 at either end of the machine, roll 17 being pressed thru 85 action of the spring 20 to pinch the traveling warp against its companion roll 16, which latter roll is rotated from pulley 21 on the roll 12 thru belt 22 to assist in feeding the warp.

This arm 19 is hung on the roll shaft 23 and is caused to oscillate by rotation of the crank disc 24 thru connecting rod 25 which is pivoted at 26 to the disc and at 27 to the oscillating arm 19.

In order to cause the warp to advance lengthwise along the elongated feed rolls and have its folds 36 lie side by side along the bar 18 supported on arms 33 beneath the same, I have provided a traversing screw 28 100

to which the warp guide eye 15 is connected. This traverse screw has the usual pawl 29 mounted in the nut 30 mounted thereon, to enter the helical groove 31 in the screw and as the screw is rotated the pawl follows the screw and causes the nut and guide eye 20 to advance along the feed rolls and upon arriving at the end of the screw the pawl is caused to follow the groove over into the return groove as best illustrated in Fig. 6, to automatically reverse its direction of travel at either end of the screw, which continues to run in the same direction.

In order to prevent this nut 30 from rotating on its screw 28, I have provided a guide arm 32 which engages and slides along the guide rod 35.

The machine is driven from the main roll shaft 23 thru clutch pulley 34 and motion is transmitted from this shaft thru sprocket chain 37 to the traverse screw 28 and thru sprocket chain 38 to the crank discs 24.

My improved warp-folding machine is very simple and practical in construction and effective in its operation and by its use the warp may be automatically hung in folds along the length of the bar, which bar may be readily removed with the warp thereon into any desired position for subsequent treatment of the warp.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a warp looping machine, a pair of elongated positively driven feed rolls, a movable guide for guiding a warp thereto, means for traversing said guide with respect to said feed rolls in a direction parallel to said feed rolls, a warp loop receiving bar, looping means for receiving said warp from said feed rolls, and means for oscillating said looping means transverse to said receiving bar, whereby the traverse movement of said guide and the oscillating movement of said looping means will deposit the warp on the receiving bar in a series of adjacent loops.

2. In a warp looping machine, a pair of elongated positively driven feed rolls, a movable guide for guiding a warp thereto, means for traversing said guide with respect to said feed rolls in a direction parallel to said feed rolls, a warp loop receiving bar, looping means comprising warp conducting rolls for receiving said warp from said feed rolls, and means for oscillating said looping means transverse to said receiving bar, whereby the traverse movement of said guide and the oscillating movements of said looping means will deposit the warp on the receiving bar in a series of adjacent loops.

3. In a warp looping machine, a pair of elongated positively driven feed rolls, a movable guide for guiding a warp thereto, means for traversing said guide with respect to said feed rolls in a direction parallel to said feed rolls, a warp loop receiving bar, looping means comprising elongated warp conducting rolls for receiving said warp from said feed rolls, and means for oscillating said looping means transverse to said receiving bar, whereby the traverse movement of said guide and the oscillating movement of said looping means will deposit the warp on the receiving bar in a series of adjacent loops.

4. In a warp looping machine, a pair of elongated positively driven feed rolls, a movable guide for guiding a warp thereto, means for traversing said guide with respect to said feed rolls in a direction parallel to said feed rolls, a warp loop receiving bar, looping means comprising two warp conducting rolls for receiving said warp from said feed rolls, resilient means for pressing said rolls towards each other, and means for oscillating said looping means transverse to said receiving bar, whereby the traverse movement of said guide and the oscillating movement of said looping means will deposit the warp on the receiving bar in a series of adjacent loops.

5. In a warp looping machine, a pair of elongated positively driven feed rolls, a movable guide for guiding a warp thereto, means for traversing said guide with respect to said feed rolls in a direction parallel to said feed rolls, a warp loop receiving bar, looping means comprising two elongated warp conducting rolls for receiving said warp from said feed rolls, a spring for pressing said rolls towards each other, and means for oscillating said looping means transverse to said receiving bar, whereby the traverse movement of said guide and the oscillating movement of said looping means will deposit the warp on the receiving bar in a series of adjacent loops.

6. In a warp looping machine, a pair of elongated positively driven feed rolls, a movable guide for guiding a warp thereto, means for traversing said guide with respect to said feed rolls in a direction parallel to said feed rolls, a warp loop receiving bar, looping means comprising two warp conducting rolls for receiving said warp from said feed rolls, a spring for pressing said rolls towards each other, means for positively driving one of said conducting rolls, and means for oscillating said looping means transverse to said receiving bar, whereby the traverse movement of said guide and the oscillating movement of said looping means will deposit the warp on the receiving bar in a series of adjacent loops.

7. In a warp looping machine, a pair of elongated positively driven feed rolls, a movable guide for guiding a warp thereto, means

for traversing said guide with respect to said feed rolls in a direction parallel to said feed rolls, a warp loop receiving bar, looping means comprising two elongated warp conducting rolls for receiving said warp from said feed rolls, a spring for pressing said rolls towards each other, means for positively driving one of said conducting rolls, and means for oscillating said looping means transverse to said receiving bar, whereby the traverse movement of said guide and the oscillating movement of said looping means will deposit the warp on the receiving bar in a series of adjacent loops.

15 In testimony whereof I affix my signature.
